UNITED STATES PATENT OFFICE

CHESTER R. MACDONALD, OF MONROE, MICHIGAN, ASSIGNOR TO THE FLINTKOTE COMPANY, OF BOSTON, MASSACHUSETTS, A CORPORATION OF MASSACHUSETTS

PROCESS AND APPARATUS FOR PRODUCING DISPERSIONS

Application filed July 22, 1927. Serial No. 207,620.

The present invention relates to improvements in a process and apparatus for producing dispersions, and refers more particularly to a process and apparatus particularly designed to efficiently produce dispersions of the type described in United States Letters Patent to Lester Kirschbraun, Nos. 1,302,810 and 1,615,303.

In the production of dispersions of the bitumen-pitch type referred to in the aforementioned patents, it has been found desirable to maintain a bulk supply of material including the end product and to subject said material repeatedly to a rapid agitation in the presence of the dispersing agent to secure exceedingly fine dispersion. In processes and apparatus now in use for producing such dispersions means are provided to cause agitation and to permit circulation of the mass to and from the zone of agitation. Such means in one type of apparatus commonly used takes the form of an open ended conduit around which the mass is caused to circulate in a container by providing agitating blades vertically mounted in the conduit and so pitched as to force the material to take a circuitous path within the containing vessel and through and around such conduit.

The circulation induced by said agitation while sufficient for most purposes is nevertheless not as thorough and complete as is desirable inasmuch as only that portion of the material which is in the immediate region of the agitating means is caused to return a number of times to the zone of agitation, while that portion of the mass which is more remote from the agitating mechanism is returned only a relatively few times to the zone of agitation. Where, for example, the agitating means is mounted vertically within said open ended conduit and the agitating blades are pitched so as to force the material downwardly through said conduit, the circulation of the mass exteriorly of the conduit is in an upward direction, involving lifting of the mass against its own weight to return it to the upper end of the conduit. Inasmuch as the burden of this lifting action must be borne by the agitating means it is sometimes found that the latter does not set up suffi-

cient forces to cause all the material to be recirculated to the zone of agitation the desired number of times.

The present invention is an improvement thereover being particularly designed to impart a positive circulation to the mass undergoing dispersion, thus insuring the return of all portions of the circulating mass to the agitating zone a number of times, resulting in the production of dispersions in which the particle size is exceedingly fine.

The utility of the invention as well as the differences between it and the prior processes and apparatus will be more particularly apparent from the following description:

One of the objects of the invention is to provide a process and apparatus in which the circulation to and from the main zone or zones of agitation is effected by positive means so that substantially all portions of the mass being dispersed will be positively and forcefully subjected a number of times to the action of the agitating mechanism during the interval between the introduction of the materials into the apparatus and the discharge of the finished product therefrom. The product produced by the process and apparatus of the present invention is characterized by a high degree of uniformity in the fineness of the dispersed particles. An advantage of the process and apparatus in which all portions of the materials undergoing dispersion are positively caused to be subjected a great number of times per given time interval to the action of agitating mechanism is that it becomes possible to increase production to a marked extent because the material will be subdivided and dispersed to the desired degree in a much shorter time.

Other objects of the invention are to provide an apparatus in which the agitating mechanism is mounted on a horizontal axis, permitting direct connections with a motor or other source of power mounted at floor levels; to provide an apparatus in which the means for imparting a forced circulation to the mass is disposed on a horizontal axis in a plane different than the plane of rotation of the agitating mechanism; to provide an apparatus in which the agitating mechanism

is located at a point where it acts upon only the lowermost portions of the mass of circulating material and while said material is moving in substantially a horizontal plane to provide an apparatus in which the agitating means may move at a relatively higher speed than the means for imparting positive circulation to the mass, thus inducing accelerated velocity of the mass while passing through the agitating zone.

The invention is characterized by simplicity, certainty in operation and economy in cost.

The foregoing and other objects will appear in the following more detailed description of one embodiment of the present invention, this embodiment being illustrated in the accompanying drawings, in which

Fig. 1 is a view taken longitudinally through the apparatus with one wall thereof removed and with certain parts broken away to more clearly disclose the structure.

Fig. 2 is a view in plan of the apparatus including the illustration of the connections of the various shafts to a power source.

Fig. 3 is a vertical sectional view taken on line 3—3 of Fig. 1.

Fig. 4 is a cross sectional view taken longitudinally through the apparatus illustrated in Fig. 1 showing a slightly modified form of construction.

Referring more in detail to the drawings, the numeral 1 indicates as a whole the apparatus which may comprise a container 2 which may be rectangular, circular or oval in shape, and of suitable depth. Disposed within the container 2 and spaced a slight distance above the bottom thereof is a shaft 3 extending through opposite side walls of the container being journalled in conventional bearings, diagrammatically illustrated at 4. The shaft 3 may be rotated by a suitable source of power such as a motor 5 directly connected thereto (particularly illustrated in Fig. 2). Between the motor 5 and one of the bearings 4 adjacent thereto the shaft 3 may be provided with a gear 6 adapted to mesh with a larger gear 7 mounted on the countershaft 8, which may be journalled in conventional bearings illustrated diagrammatically at 9. The purpose of this shaft 8 will be hereinafter more particularly brought out.

Returning now to the shaft 3 intermediate its length, it may be provided with propeller blades 10, which blades may take any desired shape or form, the particular pitch depending upon the direction of travel of the material which is subjected to the action of the blade. As illustrating one embodiment of the invention, without intending the illustration to be a limitation, the shaft may be provided with two sets of blades 11 and 12, which sets are spaced from each other, as illustrated in Fig. 1. The blades in the set

11, it is to be noted, are so pitched as to propel the material subjected to the action thereof in a clockwise direction while the blades of the set 12 may be so pitched as to impart a movement to the material being subjected to the action thereof in a counter clockwise direction, the purpose of which will be hereinafter more particularly brought out.

Returning now to the shaft 8, intermediate its length it may be provided with bevel gears 13 and 14 adapted to mesh, respectively, with bevel gears 13' and 14' mounted respectively on shafts 13'' and 14''. To the shafts 13'' and 14'' are respectively keyed rotatable elements 13^a and 13^b, which in one embodiment of the invention may take a shape resembling that of a spool having its end faces 15 enlarged. The drums 13^a and 13^b may be substantially identical in shape, and the shafts 13'' and 14'' are preferably mounted in spaced parallel relation, being suitably journaled through the front and rear walls of the container.

It is to be noted, that each of the elements 13^a and 13^b comprises enlarged ends 15 and an intermediate cylindrical hub portion gradually increasing in circumference from a point intermediate the ends outwardly to the points where the hub portion joins the ends. The diameter of the drums at the center of the hub portion is preferably about one-third to one-fourth the diameter of the discs 15, and the curvature of the body portion thereof is such that they join the inner surfaces of the ends 15 inwardly of the peripheral edge of said discs. Thus there is provided below each of the elements 13^a and 13^b an enlarged space 16 for a purpose hereinafter to be set forth. The shafts 13' and 14' are preferably spaced apart a distance somewhat greater than the end faces 15 so as to afford necessary clearance between the peripheral edges of adjacent ends.

The enlarged spaces 16 referred to above may be said to constitute the agitating zones of the present dispersing apparatus. The agitating mechanism comprising the propeller blades 10 is disposed within these zones, it being understood that the radius of the propeller blades is such that they will clear the inner surfaces of the ends 15. I have shown in each of the sets 11 and 12 three propeller blades. It is to be understood, of course, that one or more may be used and that the number in one agitating zone relative to another may differ.

As a feature of the present invention due to reduction in gearing designated diagrammatically at 6 and 7 and due to the position and size of the bevel gears 13' and 14', the drums 13^a and 13^b will be caused to rotate in opposite directions, for instance, as indicated by the arrows in Fig. 1 and at speeds materially lower than the speed of rotation of the propellers 10, the arrangement as

shown being such that the drum 13^a rotates in a clockwise direction while drum 13^b rotates counter clockwise and at a lower number of R. P. M. than the number of R. P. M. of drum 13^a. Thus, for example, where the propellers 10 rotate at a speed of 1,000 R. P. M. the drum 13^a may be driven at about 30 R. P. M. and the drum 13^b at about 20 R. P. M.

10 While it is preferable in certain instances to so gear the respective shafts that the drum 13^a will rotate in a direction opposite to the direction of rotation of the drums 13^b, dispersion may be also effectively carried on 15 with rotation of both drums in the same, rather than in opposite directions and at substantially equal speeds.

Feed pipes for introducing into the apparatus the base to be dispersed and the dispersing agent are illustrated respectively at 20 17 and 18.

In order to maintain a regulated temperature on the contents of the apparatus during the dispersing action, and in order to control the temperature, the drums 13^a and 13^b may be hollow, if desired, or they may be jacketed in an obvious manner for the reception of the temperature regulating medium which may comprise, for instance, water. In either 25 event it is preferable that the temperature regulating medium be conducted into the interior of the drum or drum jacket and out again by making the shafts 13' and 14' hollow in an obvious manner, the regulating medium being preferably led in at one end of said shafts and withdrawn out of the opposite end thereof.

In certain instances the container 2 may itself be jacketed for the purpose of temperature regulation.

40 The finished dispersion may be withdrawn through the outlet pipe 19 controlled by the gate or valve 20. The outlet pipe 19 may be positioned in the base or in the side wall of the container, the exact position being dependent upon the determination of the most efficient point for withdrawal.

In the modified type of construction illustrated in Fig. 4, there is provided means for 45 facilitating the positive circulation of the mass being dispersed by the elimination of any dead spaces, which means may comprise the trough-like elements 21 arranged substantially parallel to each other and extending transversely of the container, which may be separate or integral with the container. These trough-like elements 21 are separated from each other by the intermediate upwardly extending curved portion 22. The surfaces of the hub portions 13^a and 13^b are 55 preferably concentric with the troughs 21 to provide a curved surface facilitating directional flow of the circulating mass. The upwardly extending portion 22 as well as the 60 upwardly extending portions 23 may be pro-

vided with apertures through which the shaft 3 may extend. The construction of the container shown in Fig. 4 is generally similar to the container shown in Fig. 1 with the addition of the directional troughs. The withdrawal pipe 19 in Fig. 4 is illustrated as being connected to the side wall of the container.

The operation of the apparatus will be apparent to one skilled in the art. The materials being introduced at 17 and 18 are caused to circulate in planes generally vertical by means of the slowly revolving drums 13^a and 13^b, and these newly introduced materials as well as portions of the mass already within the container are forcefully and continuously directed to the agitating zones 75 16 where the rapidly rotating propellers 10 subject the materials to a severe agitating action under accelerated velocity to produce elongation and dispersion. The blades 10 may be preferably pitched so as to force the material being subjected to their influence to flow in substantially a horizontal direction longitudinally of the container, and the 80 material thus forced away from the region of the propellers is conveyed in substantially a circular path about the drums and back to the agitating zones. Depending upon the direction of rotation of the drums and the relative speeds at which the latter revolves, more or less of the material which has been subjected to the agitation of one of the sets of propellers will become intermingled with 85 portions of the material which has undergone agitation by having been subjected to the action of the other set and the intermingled masses will be again circulated by the revolving drums and returned to the agitating zones. Thus, it will be apparent that 90 the materials undergoing dispersion will be brought positively and repeatedly into the sphere of influence of the agitating mechanism in the interval between introduction of the materials into the apparatus and the discharge of the finished product therefrom.

By controlling the introduction of the base to be dispersed and the dispersing agent, as well as the discharge through the outlet 34, the apparatus of the present invention may be utilized either in a batch type of operation or in a semi-continuous or continuous operation, as will be readily understood by those skilled in this art.

The finished dispersion as generally produced is of sufficiently low viscosity to permit discharge in a continuous stream through the outlet 19 upon the opening of the valve 20, particularly where the outlet is located in the base of the container 2. In some instances, 125 however, depending upon the character of the starting material, the finished dispersion may be in the form of a thick heavy paste, resisting to a certain extent spontaneous flow through the outlet pipe 19, and in order to 130

facilitate the egress of such product through the discharge pipe I may utilize means for deflecting the material downwardly toward the discharge opening thereby assisting in discharging the finished product from the apparatus. This means may comprise any suitable type of instrumentality, for instance, a swingable plate member actuated by an arm or lever.

10 While I have shown only two drums, 13^a and 13^b, within one container 2, and two sets of blades 11 and 12 within the so-called agitating zones, it is to be particularly understood that a larger number of drums or sets 15 of propellers, or both, may be mounted within a single container in carrying out the principles of the present invention. Furthermore, if desired, a number of units such as described may be arranged in parallel as a 20 battery within a single container, or they may be mounted in separate containers and connected in series so that the end product of one unit of the series constitutes one of the starting materials for one of the succeeding units 25 of the series. This would be particularly desirable where one drum or a unit of two drums rotating, for instance, in opposite directions was utilized as a means for subjecting the mass to a beating action for the purpose of reducing its viscosity, thus permitting 30 the introduction and incorporation of increased quantities of base in a succeeding drum or unit of two or more drums.

Moreover, while the apparatus of the present invention has been described as particularly well suited for the production of dispersions of bitumen-pitch bases, it should be understood that other analogous procedures or functions may be performed therewith. 40 Thus, it is conceivable that the structure may serve very well (with slight modifications, if necessary) as a mere agitator or mixer for materials in either solid or liquid state, or as a stirring device for promoting solution, or 45 other union of one material with another.

It is to be understood, of course, that the connections between the side walls and base of the container shown in Fig. 1 may be rounded instead of taking the form of a right angled connection, as shown, to produce in effect the result of using the elements 21 shown in Fig. 4.

I claim as my invention:

1. An apparatus of the character described comprising, in combination, a container, rotatable means mounted on a horizontal axis for causing rapid agitation of material within said container, and non-agitating means comprising an element also mounted for rotation on a horizontal axis at an angle to the first mentioned agitating means for forcibly and positively directing material into the sphere of influence of said first named agitating means.

2. An apparatus of the character described

comprising, in combination, a container, means for causing rapid agitation of material within said container comprising elements mounted on a rotatable shaft, and non-agitating revoluble means comprising elements mounted on a shaft rotating at substantially right angles to the first mentioned shaft for forcibly and positively directing material into the sphere of influence of the first named agitating means.

3. An apparatus of the character described comprising, in combination, agitating means within said container adapted to rotate at relatively high axial speed, and non-agitating revoluble means for positively forcing material within said container into the sphere of influence of said agitating means, said revoluble means being adapted to rotate at an axial speed substantially less than that of the agitating means.

4. An apparatus of the character described comprising, in combination, a container provided with a valved outlet, means disposed in said container for subjecting material to a rapid agitation while passing in a substantially horizontal plane, means for imparting circulation of said material to and from said agitating means, comprising spool shaped drums mounted for rotation on a horizontal axis at an angle to the plane in which the agitating means rotates.

5. An apparatus of the character described comprising, in combination, a container, spool shaped drums adapted to rotate in opposite directions and circulate material upwardly and downwardly within said container, said drums having reduced hub portions providing enlarged spaces, and agitating mechanism arranged within said spaces adapted to cause rapid agitation of the circulating material.

6. An apparatus of the character described comprising, in combination, agitating means rotatable on a horizontal axis within the container, and non-agitating means rotatable on an axis extending at an angle to the axis of the agitating means for positively forcing material within the container to the sphere of influence of the agitating means.

7. A continuous process for dispersing a waterproof substance in water, which comprises maintaining a bulk supply of material comprising dispersed end product, causing portions of said bulk supply to be positively carried in mass form up and down in two opposed cyclically circulating paths, introducing to said paths fresh charges of materials to be dispersed, and during said continuous cyclic circulation subjecting said mass to rapid agitation and accelerated velocity to produce attenuation and dispersion while it is moving in a substantially horizontal plane during the lowest part of its cycle.

8. A continuous process for dispersing a waterproofing substance in water, which com-

prises maintaining a bulk supply of material comprising dispersed end product, causing portions of said bulk supply of material to be mechanically carried in mass form up and down in two opposed cyclically circulating paths, introducing to said paths fresh charges of materials to be dispersed and during such continuous cyclic circulation subjecting said mass to rapid agitation and accelerated velocity to produce attenuation and dispersion while it is moving in a substantially horizontal plane during the lowest part of its cycle.

10 In testimony whereof I affix my signature.
CHESTER R. MacDONALD.
